UNITED STATES PATENT OFFICE

JAMES F. DRISCOLL AND HARRY THOMPSON, OF ST. LOUIS, MISSOURI; SAID THOMPSON
ASSIGNOR OF ONE-SIXTH OF HIS RIGHT TO SAID DRISCOLL.

ASPHALT-HEATER.

No. 923,421.

Specification of Letters Patent.

Patented June 1, 1909.

Application filed August 1, 1908. Serial No. 446,484.

To all whom it may concern:

Be it known that we, JAMES F. DRISCOLL and HARRY THOMPSON, both citizens of the United States of America, residing at the 5 city of St. Louis, in the State of Missouri, have invented certain new and useful Improvements in Asphalt-Heaters, of which the following is a full, clear, and exact description, reference being had to the accompanying drawings, forming part of this 10 specification.

Our invention relates to the connection with a steam roller, such as employed for rolling streets or roadways, of a heater by 15 which asphalt in asphalt streets may be heated when it is desired to remove portions of the asphalt and replace the removed portions in making repairs.

The object of our invention is to provide 20 a simple, inexpensive and efficient asphalt heater that may be readily applied to any steam roller and whereby the roller may, in addition to its usual capacity, serve also as a carrier for the heater and the boiler of 25 the roller may serve as the means for supplying steam for the operation of the heater.

By the connection stated, we are enabled 30 to operate the heater at a much lower cost and with a much less expenditure of steam than that incurred in the use of an asphalt heating apparatus used exclusively for making repairs in asphalt streets and in which the steam in the apparatus is utilized as a 35 propelling power for the apparatus in addition to its utility to supply the asphalt heater.

Figure I is a side elevation of a steam roller shown in dotted lines, and our asphalt heater carried by the frame of said roller. 40 Fig. II is an enlarged front elevation of the upper portion of the hood of the heater, the connecting pipe leading thereto and the combustion chamber. Fig. III is an enlarged horizontal section taken on line III— 45 III, Fig. I. Fig. IV is an enlarged vertical section taken on line IV—IV, Fig. I, through the lower portion of the hood of the heater and one of the side guard plates. Fig. V is an enlarged vertical longitudinal 50 section taken through the heater. Fig. VI is an enlarged vertical cross section taken through the hood of the heater. Fig. VII is an enlarged top or plan view of the rear portion of the combustion chamber of the 55 heater and the steam and fuel pipes leading

to said combustion chamber. Fig. VIII is a vertical cross section taken on line VIII—VIII, Fig. V.

In the accompanying drawings: A designates a steam roller that may be of any usual type and comprises a suitable frame, a roller cylinder and a steam boiler.

1 designates the elevated combustion box of our asphalt heater which is secured to the frame of the roller A by side braces 2 and 3, the former of which are disposed horizontally and the latter of which are arranged at an incline to brace the former, as seen in Fig. I. These supports extend beyond the forward or rear end of the roller frame and the combustion box is located in front of the forward end of said frame.

The combustion box 1 preferably consists of an outer shell and a fire brick lining within said shell and it contains a combined oil and steam combustion chamber 4. At the forward end of the combustion chamber is a hollow neck into which the products of combustion are discharged from the combustion chamber 4.

6 is a steam conducting pipe leading from the steam boiler of the steam roller A and having a branch 7 that occupies a position at the rear end of the combustion box 1.

8 is an oil conducting pipe leading from an oil tank 9 supported by the steam roller A to the rear end of the combustion box and to which pipe, in conjunction with the branch 7 of the steam pipe 6, is applied a burner 10 that extends into the combustion 90 chamber 4 of said combustion box, see Fig. V. The fuel conducting pipe 8 serves to convey fuel to the burner 10 and as the fuel escapes into said burner, its combustion is promoted by steam passing over from the 95 boiler of the steam roller through the steam pipe 6 and its branch 7.

11 designates a centrally located elbow flue extending downwardly from the neck of the combustion box and 12 is a hood having at its lower end, feet 12^a whereby the hood is supported a few inches from the surface of the pavement and at its upper end a centrally located neck 13 that is slidably fitted to the flue 11. As the fuel is combusted in the combustion chamber 4 it passes from said chamber through the neck 5 into the flue 11 from which it is discharged downwardly into the hood 12 of the heater which is located in the use of the apparatus 110

immediately above the point at which the asphalt in a street is to be heated for the purpose of softening it in order that it may be removed preparatory to making a repair in the street.

In order that the products of combustion may be properly distributed beneath the hood 12 and delivered evenly over the surface to be heated, we arrange within said hood a pair of outwardly curved side deflecting plates 14 and a central dividing plate 15, see Figs. III and VI.

16 designates guards located at the sides of the hood 12 and connected to the walls of the hood by hinge links 17. These guards are adapted to be lowered to positions alongside of the walls of the hood and upon the portions of the street being heated as illustrated in the drawings in order that they will protect the surface surrounding the portions being heated and prevent the flow of heating medium to the surrounding surface. It will be seen, by reference to Figs. IV, V and VI, that the lower edge of the hood is located above the surface that is to be heated during the use of the heater and that inasmuch as the guards 16 rest upon the surface of the street, the products of combustion may escape to a slight degree between the bottom of the hood and the guards. When the guards are not in use they may be folded upwardly and onto the walls of the hood.

The hood 12 and the parts carried thereby are adapted to be elevated when the heater is not in service, by a hanger 18 that is connected to the piston rod 19 that operates in the cylinder 20 of the steam ram. Within the cylinder 20 is a piston (not shown) that 40 is adapted to be elevated under pressure of steam conducted to the cylinder from a

branch steam pipe 6^a that leads from an extension 6' of the steam conducting pipe 6. The steam pipe extension 6' leads into the flue 11 of the heater and is provided interiorly of said flue with a nozzle 21 that acts to create suction in said flue to draw products of combustion from the combustion chamber 4 and force them downwardly into the hood of the heater.

We claim:

1. In an asphalt heater, the combination of a hood, means for supporting the hood out of contact with the asphalt surface and means for delivering a heating agent to the interior of said hood downwardly through the center of the top thereof for direct play upon the asphalt surface, substantially as set forth.

2. In an asphalt heater, the combination of a hood, means for delivering a heating agent to the interior of said hood, and guards attached to said hood and adapted to rest upon the pavement apart from the hood, substantially as set forth.

3. In an asphalt heater, the combination of a hood, means for delivering a heating agent to the interior of said hood, and guards movably connected to said hood and adapted to rest upon the pavement apart from the hood, substantially as set forth.

4. In an asphalt heater, the combination of a hood, means for delivering a heating agent to the interior of said hood, and guards hinged to said hood at the bottom of its walls and adapted to rest upon the pavement apart from the hood.

JAMES F. DRISCOLL.
HARRY THOMPSON.

In presence of—

BLANCHE HOGAN,
E. M. HARRINGTON.
